UNITED STATES PATENT OFFICE.

LEE EAGER, OF ARAPAHO, OKLAHOMA TERRITORY, ASSIGNOR TO JOHN LAMOND, OF ARAPAHO, OKLAHOMA TERRITORY.

BOILER-FLUE FASTENING.

No. 808,027.

Specification of Letters Patent.

Patented Dec. 19, 1905.

Application filed August 26, 1904. Serial No. 222,277.

To all whom it may concern:

Be it known that I, LEE EAGER, a citizen of the United States, residing at Arapaho, in the county of Custer, in the Territory of Oklahoma, have invented a new and useful Improvement in Boiler-Tube Fastenings, of which the following is a specification.

My invention relates to improvements in steam-boiler flues and flue-plates or boiler-heads.

The objects of my improvements are, first, to more securely and more permanently fasten the ends of the flues to the flue-plates; second, to prevent the leakage of both steam and water; third, to prevent the burning of the flues. I attain these objects by the mechanism illustrated in the accompanying drawings, in which—

Figure I is a section of end of flue, flue-plate, and the flue nut or fastener. Fig. II is an end view of flue nut or fastener, showing it as it would appear from inside the boiler. Fig. III is a section in quarter of flue-nut, showing the supports in the water-chamber *c c'* of the nut.

A A' represent the flue, which has threads cut on the outside.

B B' represent flue-nut with threads cut on both inside and outside.

C C' represent the flue-plate with threads cut in the aperture which admits the flue.

The end of flue-nut that enters the flue-plate is composed of two parts united in the outer

end. The inner threads of the flue-nut screw onto the flue at the same time that the outer threads screw into the flue-plate, thus making a perfect rigid joint. The space which separates the inner parts of the nut forms a water-chamber *c c'*, that communicates with the water in the boiler, which admits the water well back into the nut, thus preventing it from heating or burning. Within this water-chamber are ribs or supports uniting the two parts of the nut, as shown in Figs. II and III.

I am aware that prior to my invention boiler-tube fastenings have been made containing water-space to facilitate the circulation of the water about the flue-joint. I therefore do not claim such a combination broadly; but

What I do claim as my invention, and desire to secure by Letters Patent, is—

A device of the character described, comprising a tubular extension or guard integral with the flue-sheet and a sleeve or nut having screw-threaded connection with said extension or guard upon the interior of the latter and having corresponding connection with the flue upon its exterior.

In testimony whereof I have signed my name to this specification in the presence of two subscribing witnesses.

LEE EAGER.
